UNITED STATES PATENT OFFICE.

MATHEW BEAU, OF PORT COLBORNE, ONTARIO, CANADA.

SLEIGH.

1,345,825.

Specification of Letters Patent.

Patented July 6, 1920.

Application filed December 16, 1918. Serial No. 267,088.

To all whom it may concern:

Be it known that I, MATHEW BEAU, of Port Colborne, in the county of Welland, in the Province of Ontario, Dominion of Canada, have invented certain new and useful Improvements in Sleighs, of which the following is the specification.

My invention relates to improvements in sleighs and the object of the invention is to devise a sleigh which is easily steered and turned so as to minimize the resistance offered by snow, also to devise a sleigh which will float upon the surface of the water in the form of a pontoon and in which the storage capacity is increased and it consists essentially of the following arrangement and construction of parts as hereinafter more particularly explained.

Figure 1 is a perspective view of my sleigh, a portion being broken away to exhibit the steering mechanism.

Fig. 2 is a longitudinal section immediately broken away of its length.

Fig. 3 is a cross section on line 3—3, Fig. 2.

In the drawings like characters of reference indicate corresponding parts in the various figures.

1 indicates the body of a sleigh which is provided at each end with cross pieces 2 and 3. 4 indicates orifices extending through the body 1 and cross pieces 2 and 3. 5 indicate tubes extending longitudinally of the sleigh body and forming the body of the sleigh runner, the ends of the tubes being provided with elbow-shaped ends 5^x and 5^y extending into the orifices 4 and suitably secured therein. 6 indicates flanged caps fitting into the orifices 4 so as to form closures for the open ends of the tubes 5. 7 indicates a runner member extending longitudinally of each of the tubes 5, the runner member turning up at each end so as to follow the curve of the elbow portions 5^x and 5^y.

8 indicates a metal strip extending along the edge of each runner 7. 9 indicates stay bolts provided at their lower ends with rivet heads 9^y secured in the strip 8, such stay bolts 9 extending up through the runner 7 diametrically through each tube 5 and through the body of the sleigh, the stay bolts being locked in position by nuts 9^x and 9^y bearing against the inner faces of the walls of the tubes 5 and a nut 9' threaded onto the upper end of each stay bolt against the upper face of the sleigh body 1.

10 indicates a steering post which extends vertically through the sleigh body 1 and member 2, a bearing sleeve 10^x being secured to the upper face of the member 2, such sleeve being provided with a flange 10^y through which the securing screws extend. 11 indicates a block secured to the lower face of the sleigh body 1 centrally between the tubular runners 5, such block being provided with an orifice 11^x in alignment with the orifice 10^x of the sleigh body, the lower face of the block 11 being provided with an inverted V-shaped longitudinal recess 11^y, the edges of such recess being preferably rounded off.

12 indicates a steering member which is in the form of a broad runner having an upwardly turned front end. 12^x indicates a block which is formed integral with the runner 12 and is provided at its upper face with a longitudinally extending V-shaped ridge 12^y normally fitting into the V-shaped recess 11^y. The steering post 10 extends down through the orifice 11^x as above described and through the block 12^x and runner member 12, the lower end of the post being provided with a head 10' located in a recess 12' formed in the lower edge of the steering runner 12. The head 10' is preferably an oblong head fitting into a correspondingly shaped recess, the longitudinally extending portions of the head being secured to the runner member by screws 12^z extending through the head into the runner member thereby turnably connecting the runner member 12 with the steering post 10.

13 indicates the turning wheel of the steering post. 14 indicates a compression spring which fits at its lower end around the sleeve 10^x extending upwardly around the steering post and secured in position at its upper end by a washer 14^x and nut 14^y screwed onto the steering post.

It will be readily seen that when it is desired to guide the sleigh around a curve that by turning the hand wheel 13 the runner member 12 is turned so as to carry the V-shaped rib 12^y toward a position at right angles to the recess 11^y thereby carrying the apex of the rib onto the edges of the recess producing a cam action which draws the steering post 10 down, compressing the spring 14 and allowing the steering runner 12 to assume a relatively lower position in reference to the sleigh body than the runner 7 of the sleigh.

It will thus be seen that the runner 12 is carried downward into the loose snow compressing it sufficiently solid to form a support so that by the further lowering of the 5 runner member 12 the front portion of the sleigh is lifted so that the runners are clear of the snow as the steering member is carried into the steering position. It will thus be seen that the resistance of the snow 10 against the sides of the steering runner will cause the sleigh to turn without any resistance of the sleigh runners at the front end against the soft snow as the sleigh is turned thereby allowing the sleigh to turn very 15 easily. As soon as the turning movement is completed the hand wheel is released and the compression spring 14 which is compressed by the turning of the runner 12 to the steering position draws the steering post 20 vertically upward carrying the V-shaped rib 12° back into the V-shaped recess 11° and thereby absolutely centering the sleigh runner 12 in its normal position.

In the event of the sleigh passing over ice 25 should the ice break through, the tubular runners 5 being filled with air and closed so as to be air tight, will form buoyant members for supporting the sleigh in the water. These tubular runner members may be used 30 normally as storage chambers or magazines for various materials desired to be carried therein.

From this description it will be seen that I have devised a very simple form of sleigh

which may be easily and readily turned 35 with a minimum amount of resistance in the snow, which will be buoyant in water and will give an increased storage capacity.

It will also be seen that under ordinary circumstances the bottom of the shoe of the 40 steering device is flush with the bottom of the runner and it is only when it is desired to turn that the shoe projects beneath the level of the bottom of the runner in order that the sleigh may be readily steered. 45

What I claim as my invention is:

1. In a sleigh, the combination with the sleigh body, of tubular runner bodies extending longitudinally of the sleigh body and having up-turned ends, removable 50 closures for the up-turned ends of the tubular runner bodies, and sleigh runner members extending longitudinally of the runner bodies and following at their ends the curve of the up-turned ends of such bodies. 55

2. In a sleigh, the combination with the sleigh body having a pair of orifices at each end thereof, of tubular runner bodies extending longitudinally of the sleigh body and having up-turned ends extending into 60 such orifices of the sleigh body, removable closures for such orifices, and runner members extending longitudinally of the tubular sleigh runner bodies.

MATHEW BEAU.
